UNITED STATES PATENT OFFICE

133,825

DESIGN FOR A JEWELRY FINDING OR SIMILAR ARTICLE

Alfred C. Apitz, Chicago, Ill.

Application December 26, 1941, Serial No. 104,851

Term of patent 7 years

To all whom it may concern:

Be it known that I, Alfred C. Apitz, a citizen of the United States, residing at Chicago, in the county of Cook and State of Illinois, have invented a new, original, and ornamental Design for a Jewelry Finding or Similar Article, of which the following is a specification, reference being had to the accompanying drawing, forming part thereof.

Fig. 1 is a front view of a jewelry finding showing my new design; and

Fig. 2 is an edge view looking toward the left of the design as illustrated in Fig. 1.

I claim:

The ornamental design for a jewelry finding or similar article, substantially as shown.

ALFRED C. APITZ.
